United States Patent Office.

FAYETTE S. GILES, OF NEW YORK, N. Y.

Letters Patent No. 65,208, dated May 28, 1867.

IMPROVEMENT IN STEM-WINDING WATCHES.

The Schedule referred to in these Letters Patent and making part of the same.

TO ALL WHOM IT MAY CONCERN:

Be it known that I, FAYETTE S. GILES, of the city, county, and State of New York, have invented a new and useful Improvement in Stem-Winding Watches; and I do hereby declare that the following is a full, clear, and exact description of the same, reference being had to the accompanying drawings, making a portion of this specification, in which—

Figure 1 is a plan view of the works of the watch constructed according to my invention.

Figure 2 is a detached view of certain portions of the same.

Similar letters of reference indicate corresponding parts in both figures.

This invention relates to a novel means of winding a watch by the agency of the stem thereof; and it consists in a toothed ring so combined with the spur-wheel attached to the spring-barrel, and a contrate-wheel attached to the winding-stem or arbor; that the spring-barrel may be rotated to wind the watch by a turning movement of the aforesaid stem.

To enable others to understand the construction and operation of my invention, I will proceed to describe it with reference to the drawings.

A is a spur-wheel placed upon the spindle α of the spring-barrel, and B is the spur-wheel connected with the hands of the watch. Placed within the case α' of the watch, and held in place by the overlapping edges of the screw-heads α' , is a ring, C, the internal circumference of which is toothed and gears into the wheel A, as shown in fig. 1. The winding-stem or arbor is represented at D, and has placed loose upon the cylindrical portion b of the inner end thereof a contrate-wheel, c , which gears into the teeth of the toothed ring C, and which is retained in position upon the said portion of the arbor by a slender bar, b' , which extends into a narrow groove formed circumferentially in the contrate-wheel just mentioned. The said wheel is furnished, at its innermost side, with an annular series of angular teeth, which gear into a corresponding series of similar teeth formed upon the outer side of another contrate-wheel, d , which is placed upon the square portion e of the stem or arbor D in such a manner as to be capable of sliding theron, so as to be brought away from the wheel c and into gear with the spur-wheel B, when required. A spring-lever, f , is situated just within the toothed ring C, with its extremity fitting into a groove formed circumferentially in the contrate-wheel d in such a way as to press the same out against the other contrate-wheel c . A sliding-pin, g , working through the edge of the watch-case, has its inner end resting against an enlargement, g' , formed upon the spring-lever, so that by pressing the said pin inward it will operate the aforesaid lever to move the contrate-wheel d away from the other contrate-wheel c , and bring the same into gear with the spur-wheel B, as just hereinbefore mentioned.

When it is desired to wind the watch, the stem or arbor D is turned around in the direction shown by the arrow in fig. 1, and the contrate-wheel c , being actuated by the contrate-wheel d , in contact therewith, turns the ring, which turns the spur-wheel A, and consequently rotates the spring-barrel, to the spindle α of which the said spur-wheel is attached. Instead of being moved in one direction, as just set forth, the stem or arbor D may be turned alternately in opposite directions, the contrate-wheel d yielding to allow it to be turned back during the reversed motion of the aforesaid stem, an intermittent rotary motion being in this case given to the toothed ring C.

When it is desired to set or adjust the hands of the watch the pin g is forced inward, which brings the wheel d away from the wheel c , thus bringing the wheel d into gear with the wheel B, and allowing the stem D to turn within the wheel c without operating the same, which being done, the stem D is turned in one direction or the other, as the case may require, and operates the wheel B to bring the hands to the desired position.

What I claim as my invention, and desire to secure by Letters Patent, is—

The toothed ring C, in combination with the spur-wheel A of the spring-barrel, and the contrate-wheel c attached to the winding-stem or arbor, substantially as and for the purpose herein set forth.
